ELECTRIC FOOTBALL GAME

George L. Schuh, 4910 Lila Ave., Pleasure Ridge Park, Ky., and Robert P. Bowlds, 3000 Dale Ann Drive, Louisville, Ky.

Filed June 17, 1960, Ser. No. 36,997
10 Claims. (Cl. 273—94)

This invention relates to game apparatus, and more particularly to an electrically operated game apparatus simulating the game of football.

A main object of the invention is to provide a novel and improved electrically operated game apparatus for simulating the game of football and for enabling two players to compete in the movement of a game piece on a simulated football field according to the rules of football and to employ strategy similar to that employed in an actual football game.

A further object of the invention is to provide an improved game apparatus for simulating the game of football, the apparatus involving relatively simple components, being easy to operate, and enabling two opposing players to use their skill and knowledge of the game of football in analyzing situations resembling those occurring in an actual game and in attempting strategic maneuvers similar to those which would be attempted under actual playing conditions.

A still further object of the invention is to provide an improved electrically operated game apparatus arranged to allow two opposing players to compete in a simulated football game, the apparatus being relatively compact in size, being durable in construction, and providing a high degree of entertainment by accurately simulating actual situations which might arise in a game of football, including unexpected strategic actions on the part of the opposing teams, the imposition of penalties, and the occurrence of various other events which might conceivably occur in an actual game of football and which ordinarily would call for suitable tactics on the part of one or the other of the opposing teams.

A still further object of the invention is to provide an improved game apparatus for playing a simulated football game, the apparatus being completely portable, being easy to set up for use, and enabling two opposing players to test their knowledge of the game of football and their ability to successfully select and employ suitable tactics in accordance with various situations similar to those which might arise in actual football game.

Further objects and advantages of the invention will become apparent from the following description and claims, and from the accompanying drawings, wherein:

FIGURE 1 is a top plan view of an improved electrically operated football game apparatus constructed in accordance with the present invention.

FIGURE 2 is an enlarged fragmentary perspective view of one end portion of the apparatus of FIGURE 1, showing one of the hidden play-selecting switches forming a part of the apparatus.

FIGURE 3 is an enlarged perspective view of the playing piece employed in the apparatus of FIGURE 1, said playing piece simulating a football.

FIGURE 4 is an enlarged fragmentary end elevational view taken on the line 4—4 of FIGURE 1 and showing the ten-yard marker employed with the simulated football field of the game apparatus.

FIGURE 5 is an enlarged fragmentary top plan view of the game apparatus of FIGURE 1 with the top cover of the housing portion thereof removed.

FIGURE 6 is a fragmentary transverse vertical cross sectional view taken substantially on the line 6—6 of FIGURE 5.

2

FIGURE 7 is a fragmentary transverse vertical cross sectional view taken substantially on the line 7—7 of FIGURE 5.

FIGURE 8 is a longitudinal vertical cross sectional view taken on the line 8—8 of FIGURE 6.

FIGURE 9 is a fragmentary horizontal cross sectional view taken substantially on the line 9—9 of FIGURE 7, with the play-selecting switches in non-corresponding positions, whereby to provide a successful play indication on the apparatus.

FIGURE 10 is an enlarged vertical cross sectional detail view taken substantially on the line 10—10 of FIGURE 5.

FIGURE 11 is a vertical cross sectional view taken on the line 11—11 of FIGURE 10.

FIGURE 12 is a schematic wiring diagram showing the electrical connections of the game apparatus of FIGURES 1 to 11.

Referring to the drawings, the game apparatus is designated generally at 13 and comprises a game board 14 on one end portion of which is provided a generally rectangular housing 15 having the horizontal top cover 16. The remainder of the game board 14, namely, the portion other than that contained in the housing 15 is inscribed with a simulated football field 17.

The simulated football field 17 comprises the grid-like markings comprising the transverse yardage lines 18 spaced apart by even intervals representing five yard increments in yardage, and is further inscribed with the longitudinally extending parallel lines 19 spaced apart by even distances representing intervals between the respective opposite side lines 20 and 21. A simulated football 22 is mounted on a supporting base 23 which is adapted to be moved over the simulated football field 17 to simulate the movement of the football in an actual football game, the base 23 being provided at the intermediate portions of its opposite side edges with opposing index marks 24 enabling the playing piece to be accurately positioned on the simulated football field 17 in accordance with its actual position as determined by the apparatus in a manner presently to be described.

A longitudinally extending rod-like bracket member 25 is mounted adjacent one of the side lines 20 at the marginal portion of the game board, and slidably mounted on the rod-like member 25 is a simulated ten-yard marker 26, which comprises a plate-like member 27 substantially equal in length to the distance defined by two simulated five-yard intervals on the simulated football playing field 17, the member 26 being provided with upstanding supporting lugs 28, 28 at its outer corner portions which are slidably engaged on the rod-like support member 25. An outwardly extending operating tab 29 is formed on the outer edge of the member 26 to facilitate the movement of the member along the rod 25.

As will be readily understood, the member 26 is employed to establish the required forward distance which a player must gain in the four downs allowed when the player obtains possession of the ball.

The cover member 16 of housing 15 is provided with respective scoring indicators, comprising a yardage-indicating disc 30 which is rotatably mounted adjacent the lower right hand corner of the cover 16, and which is disposed subjacent the bottom surface of the cover, being provided with an upstanding operating knob 31 extending above the top surface of the cover member 16. A viewing window 32 is provided in the cover, and the disc 30 is inscribed with respective indicia, corresponding to the required number of yards to be gained by a team in possession of the ball, whereby the disc 30 may be set after each play to indicate this required yardage. Respective score-indicating pairs of disc members 33, 33

and 34, 34 are similarly rotatably mounted adjacent the upper opposite corners of the cover member 16, the disc members 33 and 34 being provided with numerals which may be positioned beneath respective pairs of viewing windows 35, 35 and 36, 36 provided in the cover member 16, the respective pairs of discs 33, 33 and 34, 34 being manually settable to indicate the scores of the respective opponents. As in the case of the yardage-indicating disc 30, the score-indicating discs 33, 33 and 34, 34 are provided with upstanding knob members 37 for manually setting the score-indicating discs, as required.

Designated generally at 39 is a variable play indicator comprising a drum 40 which is rotatably mounted at its ends on a pair of upstanding bracket members 41 and 42, the bracket members 41 and 42 having vertical supporting portions extending transversely, whereby the drum member 40 is mounted for rotation on a longitudinal horizontal axis by its shaft elements 43, 43. The surface of the drum member 40 is inscribed with ten columns of indicia designated at 41 to 50 representing various play results for different respective football play situations, namely, "kick-off," "no gain," "punt," "end run," "kick and punt return," "pass," "field goal," "line buck," "quick kick," and "point after touchdown." The top cover 16 is formed with an elongated longitudinal slot 51 which overlies the top portion of the surface of the drum 40 and which exposes the top portions of the indicia columns 41 to 50, except that respective pivoted covers 52 to 56 are provided at one side margin of the slot 51, transversely overlying the slot, and normally covering the portions of the indicia columns 41, 43, 45, 49 and 50. Thus, the pivoted covers 52 to 56 normally cover the play result information with respect to "kick-off," "punt," "kick and punt return," "field goal," "quick kick," and "point after touchdown." The pivoted covers 52 to 56 are provided with upwardly and rearwardly inclined tab elements 57 which may be manually depressed to raise the main body portions of the covers and to expose the subjacent play result-indicating columns to view.

Designated at 58 is an electric motor which is mounted on the horizontal bottom wall 59 of housing 15 adjacent one end of the drum 40 and which is gearingly coupled to the drum by a pinion gear 60 mounted on its shaft which meshes with a gear 61 secured to the end of the drum 40. Energization of motor 58 therefore rotates the drum 40.

Designated at 62 is a penalty-indicating drum which is rotatably mounted rearwardly adjacent the drum 40 on the upstanding brackets 42 and 64, the top cover 16 being provided with a viewing slot 65 located immediately above the top portion of the peripheral surface of the drum 62. Drum 62 is provided with two columns of indicia, shown at 66 and 67, arranged in side-by-side relationship and being readable through the viewing slot 65. The indicia columns 66 and 67 provide information with regard to the nature and the amount of penalties, and whether the penalties are offensive or defensive.

As will be readily understood, the penalty drum 62 rotates simultaneously with the main play result-indicating drum 40, but the information thereon is not used unless the penalty indicating lamp 68, located adjacent the drum 62, becomes energized.

Designated respectively at 69, 70, 71 and 72 are play-indicating signal lamps which are mounted on suitable brackets located in the forward portion of the housing 15, the brackets being provided with sockets supporting the lamps 69 to 72, and the top cover 16 being apertured to expose the upper portions of said lamps. The top portion of the cover 16 is likewise apertured to expose the upper portion of the penalty lamp 68, previously mentioned.

The lamps 69 to 72 are respectively associated with certain definite play situations, namely, "no gain or loss," "end run," "pass," and "line buck." In general, the signal lamp 69 is associated with an unsuccessful play

on the part of an offensive player, so that when the lamp 69 becomes energized, the play result is read from the column 42 of drum 40. The remaining signal lamps 70, 71 and 72 are associated with successful play attempts on the part of an opposing player, and energization of these lamps, in a manner presently to be described, indicates that the play result will be determined from corresponding information columns on the drum 40.

As will be presently described, manually operated selecting switch means is provided for each of the opposing players to prepare circuits for energization of one of the lamps 69 to 72 simultaneously with the energization of the motor 58, in accordance with different relative settings of the manual switch-operating means.

It will be understood that the offensive player attempts to energize a selected one of the lamps 70, 71 or 72, to indicate favorable travel of the ball for his team, whereas the defensive player attempts to anticipate the play selected by the offensive player and attempts to position his manually operated switch in the same relative position as that of the offensive player, thereby preventing energization of the lamps 70, 71 and 72 and instead causing the "no gain" lamp 69 to become energized.

Slidably mounted on the bottom wall 59 in the rear portion of the housing 15 are a pair of longitudinally extending, longitudinally movable, parallel, adjacent bar members 73 and 74 of insulating material, and being formed with longitudinal slots 75 through which extend vertical guide pins 76 which guide the bar members for longitudinal movement. An operating lever 77 is pivoted at 78 to bottom wall 59 and has a handle portion 79 extending through a horizontal slot 80 formed in the right end wall 81 of housing 15. The lever 77 is provided with an inner arm formed at its end with a generally circular cam element 82 which engages in a generally circular notch 83 formed in the right end portion of the bar 74, whereby said bar may be moved longitudinally responsive to rotation of the lever 77 by a player operating the exposed handle portion 79.

At the left end of the device, a similar operating lever 84 is provided which has an exposed handle portion 85 and which is provided with an inner arm having a generally circular cam portion 86 which engages in a generally circular notch 87 formed in the left end portion 45 of the bar 73, whereby a player may move the bar 73 longitudinally by moving the exposed handle portion 85. Since the handle portions 79 and 75 extend through opposed end walls of the housing, said handle portions are substantially shielded from each other, so that one opposing player ordinarily cannot see the setting of the other player's play-selecting handle portion.

The end walls of the housing are provided with spaced indicia located over the slots 80, indicating three different plays which may be selected by a player, selection being made by movement of the associated handle portion 79 or 85 to a position aligned with the specific selected play, as will be apparent from FIGURE 2, wherein, for example, the handle portion 79 is in a centered position directly subjacent the indicia "pass," indicating that this is the play selected.

Designated at 88 is a spring contact arm which is secured to the intermediate portion of the bar member 74 and which extends over the bar member 73. The contact arm 88 is selectively engageable with any one of five different spaced contact members 89 to 93 secured on the bar member 73, and being selectively engageable therewith in accordance with the five different relative positions which can be established for the bar members 73 and 74 in accordance with the five different relative settings which can be obtained of their associated operating handles 79 and 85.

It will be noted that the contacts 89, 90, 92 and 93 are electrically connected to a common wire 94, and that one terminal of each of the lamps 70, 71 and 72 is connected to said wire 94. The remaining contact, namely the

contact 91, is connected by a wire 95 to one terminal of the "no gain" lamp 69.

Designated at 96 is a switch arm which is pivotally mounted on a supporting bolt 97 secured in the rear wall 98 of housing 15 at the intermediate portion thereof. The lever 96 extends upwardly through a generally T-shaped aperture 99 formed in the cover 16, said aperture including the central notch 100 through which the upstanding portion of the lever 96 is at times movable. The switch arm 96 is biased rearwardly by a coiled spring 101 mounted on the bolt 97 and bearing between the intermediate portion of the arm 96 and a bearing nut 102 provided on the forward portion of the bolt. Therefore, the switch arm 96 is biased to a vertical position in alignment with the opposite end portions of the slot 99. When the switch arm 96 is in its centered, vertical upstanding position, it may be rotated forwardly against the biasing force of the spring 101 to engage with a yieldable contact arm 103 suitably mounted on the upper portion of the rear wall 98, being offset in the manner illustrated in FIGURE 7 to allow contact therewith to be established responsive to the counterclockwise rotation of the switch arm 96, as viewed in FIGURE 7. Contact arm 103 is connected by a wire 104 to one terminal of the motor 58. The opposite terminal of motor 58 is connected by a wire 105 to the positive terminal of a flashlight battery assembly 106 mounted in the housing 15. The negative terminal of the flashlight battery assembly 106 is connected by a wire 107 to the bolt member 97, whereby the motor 58 becomes energized responsive to the engagement of the conductor switch arm 96 with the contact arm 103.

The contact arm 88, carried by the bar member 74 is connected to the positive battery wire 105, as shown in FIGURE 12.

A pair of spring contact arms 110 and 111 are mounted on the rear wall 98 in positions to be engaged responsive to opposite rotation of the switch arm 96. Thus, when the switch arm 96 is rotated in a clockwise direction, as viewed in FIGURE 12, it is engageable with the contact member 110, whereas when it is rotated in a counterclockwise direction, as viewed in FIGURE 12, it is engageable with the stationary contact member 111.

Transversely extending spaced bridging contact members 113, 114 and 115 are secured to the bottom wall 59 of housing 15 subjacent the adjacent longitudinal margins of the bar members 73 and 74, extending beneath said margins and being selectively engageable by respective depending contact elements 116 and 117 secured to said bar members. Since the bridging contact members 113, 114, and 115 extend transversely, bridging contact between the contact elements 116 and 117 is established only when the bar members 73 and 74 have been moved into corresponding, namely, similar play-indicating, positions by their associated operating handles 79 and 85. When the bar members 74 and 73 are not in corresponding, or similar play-indicating, positions, the contact elements 117 and 116 will engage different ones of the three transversely extending stationary bridging contact members 113, 114 and 115.

As shown in FIGURE 12, the stationary switch contact element 110 is connected to the depending contact element 117 by a wire 118, and the opposing stationary switch contact element 111 is connected to the depending contact element 116 by a wire 119.

As previously stated, one terminal of each of the lamps 70, 71 and 72 is connected to the wire 94. The remaining terminal of the lamp 70 is connected by a wire 120 to the bridging contact 113. The remaining contact of the lamp 71 is connected by a wire 121 to the bridging contact 114. The remaining contact of the lamp 72 is connected by a wire 122 to the bridging contact 116.

As previously mentioned, one terminal of the "no gain" lamp 69 is connected by the wire 95 to the contact ele-

ment 91 on the bar member 73, said contact element 91 being engageable by the resilient contact arm 88 when the bar members 73 and 74 are in positions corresponding to the same selected position of the operating handles 79 and 85. The remaining terminal of the "no gain" lamp 69 is connected by a wire 123 to a pair of opposite contacts 124 and 125 mounted on the rear wall 98 and arranged to be engaged by the lower portion of the switch arm 96 responsive to rotation of said switch arm in either direction, namely, in a direction to engage either the contact 103 or the contact 111. As will be seen from FIGURE 12, when the bar members 73 and 74 are in corresponding positions, namely, positions corresponding to the same settings of the operating handles 79 and 85, the "no gain" lamp 69 will be energized when the switch arm 96 is rotated from its centered position to a position engaging either the contact 125 or the contact 124 by a circuit comprising the positive terminal of the battery assembly 106, the wire 105, the contact element 88, contact member 91, wire 95, the lamp 69, the wire 123, either of the contacts 124 or 125, the switch arm 96, the wire 107, and the negative terminal of the battery assembly 106. Under these circumstances, none of the successful play-indicating lamps 70, 71 and 72 can be energized, since none of the contacts 89, 90, 92 or 93 is engaged by the contact arm 88. However, when the play-selecting arms 79 and 85 are in different positions, the contact arm 88 engages one of the contact elements 89, 90, 92 or 93, and allows one of the play-indicating signal lamps 70, 71 or 72 to be energized. The energizing circuit for the lamp 70 would thus include the wire 120, the bridging contacts 113, and either contact element 117 or 116, depending upon whether the switch arm 96 was moved into engagement with contact 110 or contact 111, namely, as to which player was the offensive player at that time. The circuit for the lamp 70 would thus comprise the positive terminal of the battery assembly 106, the wire 105, the contact element 88, one of the contact elements 89 or 90, the wire 94, 40 the lamp 70, the wire 120, the bridging contact 113, and either of the contact elements 117 or 116, connected to contact elements 110 or 111 and engaged by the switch arm 96, which is in turn connected to the negative terminal of the battery assembly 106 by the wire 107. The other successful play-indicating lamp 71 or 72 will be energized in a similar manner, depending upon the setting of the operating handle of the selecting switch by the offensive player.

It will be understood that when a play is selected by the offensive player, the defensive player attempts to guess the selected play and set his operating handle to a position calculated to match that of the setting of the selecting switch operating handle of the offensive player. If the defensive player is successful, he succeeds in energizing the "no gain" lamp 69 when the switch arm 96 is rotated by the offensive player subsequent to the spinning of the drum 40. If the defensive player is unsuccessful in matching the play selected by the offensive player, one of the successful play-indicating lamps 70, 71 or 72 becomes illuminated, in accordance with the selection of the offensive player, when the offensive player operates the switch arm 96 following the spinning of the indicating drum 40.

Secured on the shaft of the motor 58 is a disc 130 carrying a contact element 131 which is engageable in a predetermined position of the shaft with a stationary contact 132 mounted on and suitably insulated from the upstanding bracket 42. Disc 130 is connected to the wire 105, for example, by a contact brush 134 which slidably engages the periphery of the disc, the brush 134 being suitably mounted on the top portion of the upstanding bracket member 42, in the manner illustrated in FIGURE 5.

As shown in FIGURE 12, one terminal of the penalty lamp 68 is connected to the wire 123. The remaining terminal of lamp 68 is connected by a wire 140 to

the contact element 132. Thus, when the contact element 131 engages the stationary contact element 132, a circuit is completed which will enable the penalty lamp 68 to become energized responsive to the movement of the switch arm 96 into engagement with either of the contacts 124 or 125. This circuit comprises the negative terminal of the battery assembly 106, the wire 197, the switch arm 96, either contact 124 or 125, the wire 123, the penalty lamp 68, the wire 140, the contact 132, the contact element 131, the brush 134, the wire 105, and the positive terminal of the battery assembly 106.

In using the device, the opposing players are located at opposite sides thereof, one player being located on the side containing the operating handle 79 and the other player being located on the side containing the operating handle 85. The general procedure is the same as that in the actual game of football, the first player energizing the motor 58 by first moving the switch arm 96 forwardly against the force of the biasing spring 101, as above described, whereby the drum 40 is rotated, and whereby the penalty drum 62 is likewise rotated. This first operation represents "kick-off," and the results of this play may be determined by lifting the cover member 52. The other player then takes possession of the ball, the ball being placed at the position indicated by the information obtained from the column 41. The ten-yard marker 26 is properly positioned to indicate the required ten yard gain to be made in a series of four downs by the offensive player, similar to the manner in which such a marker is employed in the actual game of football. The offensive player is then allowed to undertake a series of plays to attempt to make the required yardage, as in the actual game of football, the offensive player setting his operating handle 79 or 85 in accordance with a selected play which he desires to use, and the defensive player attempts to anticipate said selection by setting his operating handle to a position calculated to match that of the operating handle of the offensive player. The offensive player then rotates the switch arm 96 forwardly to spin the drums 40 and 62, after which the switch arm 96 is allowed to resume its vertical position and the offensive player then rotates the switch arm laterally, namely, in its own plane to engage either the contact 111 or 110. This will energize either the "no gain" lamp 69, or one of the successful play-indicating lamps 70, 71 or 72, depending upon the relative position of the bar members 74 and 73, as above explained. The specific detailed information with regard to play results will be obtained from the drum 40, and this information will depend upon whether the play was successful or whether it failed. Failure is indicated by the energization of the "no gain" lamp 69, and the resultant progress of the ball will be indicated by the information on the column 42 of the drum 40. Such information may consist of "no gain," or an actual loss in yardage, which requires that the playing piece 22 be moved rearwardly. On the other hand, if the success of the player is indicated by energization of one of the lamps 70, 71 or 72, the specific yardage information is obtainable from the corresponding column on the drum 40, whereby the offensive player will move the playing piece 22 in accordance with the information thus received.

It will be noted that the information on the drum not only provides for forward and rearward movement of the playing piece 22, but also for lateral movement, resulting at times in an "out-of-bounds" situation whose significance is similar to that occurring in an actual game of football and which is treated accordingly.

If the penalty lamp 68 becomes energized by engagement of contact element 131 with the stationary contact 132, as above described, a penalty is indicated, and the penalty may be either against the offensive or the defensive player, in accordance with the exposed information provided by the drum 62.

The results of play executed by an offensive player other than "line buck," "pass," and "end run," may be

obtained by merely first energizing the motor 58 by rotating the switch arm 96 forwardly, in the manner above described, after which said switch arm is released, and the corresponding cover element 52 to 56 is raised to show the results of such a play.

It will be noted that the simulated playing field on the board 14 is provided with respective alphabetical indicia "A" and "B" on the opposite sides adjacent the side lines 20 and 21. These designations are employed in establishing lateral movements of the playing piece, the information provided on the drum 40 including designations of such lateral movements. Thus, for example, the column 44 which gives the play results for "end runs" contains designations such as "4 A-6 Yards" indicating a movement of four intervals or columns toward the "A" side line as well as a forward movement of six yards.

The fact that the ball moves towards the sidelines on successful or unsuccessful plays adds an element of strategy and presents a definite mental challenge to players. It is obviously advantageous to the offensive player to keep the ball in the center of the playing field to prevent going out of bounds on gains accomplished, so that the position of the ball on the field is a factor to be considered before choosing a play, since "pass," "end run" and "line buck" gains have different amounts of lateral movement. Specifically, the "pass" gains have no lateral movement and the "line buck" average lateral movement is less than that of the "end run."

Where the results of a play carry the simulated football playing piece 22 outside of the side lines 21 or 20, an "out-of-bounds" situation is present, and is treated in the same manner as in the actual game of football.

While a specific embodiment of an improved electric football game has been disclosed in the foregoing description, it will be understood that various modifications within the spirit of the invention may occur to those skilled in the art. Therefore, it is intended that no limitations be placed on the invention except as defined by the scope of the appended claims.

40 What is claimed is:

1. In an electric football game, a game board simulating a football playing field, a movable playing piece, a support adjacent said game board, a variable play result indicator mounted on said support, a plurality of play-indicating signal lamps, a pair of manually movable play-selecting members at opposite ends of the support, each having a similar series of predetermined play-selecting settings, cooperating movable switch members mechanically connected respectively to said play-selecting members, and means to energize different lamps in accordance with different relative positions of said switch members, as established by selected play-selecting settings of the movable play-selecting members.

2. In an electric football game, a support, a play result indicator having markings simultaneously indicating play results of different types of plays in terms of forward and lateral movement of a football, a plurality of play-indicating signal lamps, a pair of manually movable play-selecting members at opposite remote locations on the support, each having a similar series of predetermined play-selecting settings, cooperating movable switch members mechanically connected respectively to said play-selecting members, and means to energize different lamps in accordance with different relative positions of said switch members, as established by selected play-selecting settings of the movable play-selecting members.

3. In an electric football game, a support, a variable play result indicator on said support having markings simultaneously indicating play results of different types of plays, respective signal lamps associated with different types of plays, a pair of manually movable play-selecting members at opposite remote locations on said support, each having a similar series of predetermined play-selecting settings, cooperating movable switch members mechanically connected respectively to said play-select-

ing members, means to energize different lamps in accordance with different relative positions of said switch members, as established by selected play-selecting settings of the movable play-selecting members, and means to energize a common signal lamp when the play-selecting members are at similar settings.

4. In an electric football game, a support, a variable play result indicator on said support having markings simultaneously indicating play results of different types of plays, a penalty indicator, a penalty lamp, respective signal lamps associated with the different types of plays, a pair of manually movable play-selecting members at opposite remote locations on said support, each having a similar series of predetermined play-selecting settings, cooperating movable switch members mechanically connected respectively to said play-selecting members, means to energize different lamps in accordance with different relative positions of said switch members, as established by selected play-selecting settings of the movable play-selecting members, means to energize a common signal lamp when the play-selecting members are at similar settings, and means to at times connect said penalty lamp to said source simultaneously with the energization of a play-indicating signal lamp.

5. In an electric football game, a support, a variable play result indicator on said support having markings simultaneously indicating play results of different types of plays, a changeable penalty indicator, a plurality of signal lamps, each signal lamp being associated with a different type of play, a penalty lamp, a pair of manually movable play-selecting members at opposite remote locations on the support, each having a similar series of predetermined play-selecting settings, cooperating movable switch members mechanically connected respectively to said play-selecting members, means to energize different lamps in accordance with different relative positions of said switch members, as established by selected play-selecting settings of the movable play-selecting members, means to energize a common signal lamp when the play-selecting members are at similar settings, and means to at times connect said penalty lamp to said source simultaneously with the energization of a play-indicating signal lamp.

6. In an electric football game, a support, an electrically operated variable play result indicator on said support having markings simultaneously indicating play results of different types of plays, respective signal lamps mounted on the support and associated with the different types of plays, a pair of parallel spaced multiple contact switch bars slidably mounted on said support, stationary contact means on the support engageable with the contacts on said switch bars, a pair of manually movable play-selecting members mounted at remotely opposite locations on said support and having a series of similar play-selecting settings, means mechanically coupling said play-selecting members to the respective switch bars, means to energize any one of a selected group of signal lamps through said switch bars and stationary contact means in accordance with different relative positions of said switch bars as established by different play-selecting settings of the play-selecting members, and means to energize a common further signal lamp through the contacts of the switch bars when the play-selecting members are at corresponding settings.

7. In an electric football game, a support having vertical opposite ends, an electrically operated variable play result indicator on said support having markings simultaneously indicating play results of different types of plays, respective signal lamps mounted on the support and associated with the different types of plays, a pair of parallel spaced multiple contact switch bars slidably mounted on said support, stationary contact means on the support engageable with the contacts on said switch bars, a pair of manually movable play-selecting members mounted respectively at said vertical opposite ends of said support and having a series of similar play-selecting

settings, means mechanically coupling said play-selecting members to the respective switch bars, means to energize any one of a selected group of signal lamps through said switch bars and stationary contact means in accordance with different relative positions of said switch bars as established by different play-selecting settings of the play-selecting members, and means to energize a common further signal lamp through the contacts of the switch bars when the play-selecting members are at corresponding settings.

8. In an electric football game, a support, an electrically operated variable play result indicator on said support having markings simultaneously indicating play results of different types of plays, respective signal lamps mounted on the support and associated with the different types of plays, a pair of parallel spaced multiple contact switch bars slidably mounted on said support, stationary contact means on the support engageable with the contacts on the switch bars, a pair of manually movable play-selecting members mounted at remotely opposite locations on said support and having a series of similar play-selecting settings, means mechanically coupling said play-selecting members to the respective switch bars, means to simultaneously energize said variable play result indicator and to energize any one of a selected group of signal lamps through said switch bars and stationary contact means in accordance with different relative positions of said switch bars as established by different play-selecting settings of the play-selecting members, means to energize a common further signal lamp through the contacts of the switch bars when the play-selecting members are at corresponding settings, an electrically operated changeable penalty indicator mounted on the support, and means to at times energize said penalty indicator responsive to the energization of said variable play result indicator.

9. In an electric football game, a support having vertical opposite ends, an electrically operated variable play result indicator on said support having markings simultaneously indicating play results of different types of plays, respective signal lamps mounted on the support and associated with the different types of plays, a pair of parallel spaced multiple contact switch bars slidably mounted on said support, stationary contact means on the support engageable with the contacts on the switch bars, a pair of manually movable play-selecting members mounted respectively at said vertical opposite ends of said support and having a series of similar play-selecting settings, means mechanically coupling said play-selecting members to the respective switch bars, means to simultaneously energize said variable play result indicator and to energize any one of a selected group of signal lamps through said switch bars and stationary contact means in accordance with different relative positions of said switch bars as established by different play-selecting settings of the play-selecting members, and to simultaneously energize said variable play result indicator, means to energize a common further signal lamp through the contact of the switch bars when the play-selecting members are at corresponding settings, an electrically operated changeable penalty indicator mounted on the support, and means to at times energize said penalty indicator responsive to the energization of said variable play result indicator.

10. In an electric football game, a support, an electrically operated variable play result indicator on said support having markings simultaneously indicating play results of different types of plays, respective signal lamps mounted on the support and associated with the different types of plays, a pair of parallel spaced multiple contact switch bars slidably mounted on said support, stationary contact means on the support engageable with certain contacts on said switch bars, a pair of manually movable play-selecting members mounted at remotely opposite locations on said support and having a series of similar play-selecting settings, means mechanically coupling said play-selecting members to the respective switch bars,

means to energize any one of a selected group of signal lamps through said switch bars and stationary contact means in accordance with different relative positions of said switch bars, as established by different play-selecting settings of the play-selecting members, and to simultaneously energize said variable play result indicator, and means to energize a common further signal lamp through the contacts of the switch bars when the play-selecting members are at corresponding settings.
